(57) **CLAIM**

The ornamental design for a tubing holder, as shown and described.

DESCRIPTION

FIG. 1 is a top-front-right perspective view of a tubing holder showing my new design according to a first embodiment;

FIG. 2 is bottom-front-left perspective view thereof;

FIG. 3 is an enlarged front elevational view thereof;

FIG. 4 is an enlarged rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is a left-side elevational view of a second embodiment of the tubing holder, the second embodiment being identical to the first embodiment except that the second embodiment has broken away symbols that indicate that any portion of the article beyond what is shown forms no part of the claimed design; and,

FIG. 10 is a top-front-right perspective view of the tubing holder according to the first embodiment, shown with a tube attached.

The broken lines shown in the drawings are for illustrative purposes only and form no part of the claimed design.
